UNITED STATES PATENT OFFICE.

JAMES M. WALDRON, OF ENGLEWOOD, NEW JERSEY, AND JOHN P. COLEMAN, OF EDGEWOOD BOROUGH, PENNSYLVANIA.

RAILWAY-SWITCH-OPERATING APPARATUS.

1,300,307.

Specification of Letters Patent.

Patented Apr. 15, 1919.

Application filed December 12, 1917. Serial No. 206,725.

To all whom it may concern:

Be it known that we, JAMES M. WALDRON and JOHN P. COLEMAN, citizens of the United States, residing, respectively, at Englewood, in the county of Bergen and State of New Jersey, and at Edgewood borough, in the county of Allegheny and State of Pennsylvania, have invented certain new and useful Improvements in Railway-Switch-Operating Apparatus, of which the following is a specification.

Our invention relates to railway switch operating apparatus.

One feature of our invention is the provision, in combination with a switch the points of whose switch rails are staggered longitudinally with relation to the track, of two separate operating members, staggered to correspond to the staggering of the switch points, for positively and directly actuating said switch rails, and a motion plate having two cam slots spaced in accordance with the staggering of the rail points for actuating said operating members.

Another feature of our invention is the provision, in combination with a railway switch and an operating mechanism therefor comprising a motion plate, of a novel and improved circuit controller governed separately by the two switch rails and by the motion plate for insuring that one switch rail or the other, depending on the position of the motion plate, shall be closed properly against its stock rail in order that the indicated circuit may be closed.

Still another feature of our invention is the provision, in switch operating apparatus, of an easily replaceable weak member of novel construction in the connection between the operating mechanism and a switch rail, for avoiding injury to the operating mechanism in the event that the switch rail is moved by a car or train trailing through the switch, and for insuring that the operating member shall yield in case of such trailing and so avoid the danger of derailment due to the wheels mounting the switch rail without opening it.

We will describe one form of apparatus embodying our invention, and will then point out the novel features thereof in claims.

In the accompanying drawings, Figure 1 is a plan view showing a railway switch having applied thereto one form of operating

apparatus embodying our invention. Fig. 2 is a vertical longitudinal sectional view taken on the line II—II in Fig. 1 looking in the direction indicated by the arrows. Fig. 3 is a transverse vertical sectional view taken on the line III—III of Fig. 1 looking in the direction indicated by the arrows. Fig. 4 is a top plan view, with cover removed, of a circuit controller C shown in Fig. 1. Fig. 5 is a sectional view taken on the line V—V of Fig. 4, looking in the direction indicated by the arrows, the drum 28, however, being shown in elevation. Fig. 6 is a sectional view taken on the line VI—VI of Fig. 1 and of Fig. 4 looking in the direction indicated by the arrows, and showing the means for operating a portion of the circuit controller C. Fig. 7 is a sectional view taken on the line VII—VII of Fig. 1 and of Fig. 4, looking in the direction indicated by the arrows, and showing the means for operating the two other parts of the circuit controller C. Fig. 8 is a diagrammatic view showing one arrangement of circuits which may be used in connection with the circuit controller C shown in certain of the preceding views.

Similar reference characters refer to similar parts in each of the several views.

Referring first to Fig. 1, we have here shown a railway switch comprising the usual stock rails 1 and 1^a, and the usual movable rails or switch rails 2 and 2^a. The points of these switch rails are staggered longitudinally with respect to the track, that is, the point of rail 2 is some distance, preferably about 18 inches, in advance of the point of rail 2^a. As is already understood in the art, the purpose of this staggering is as follows: When the switch is set for the turnout from the straight track (which is the position in which it is shown in the drawing), and a car or train is moving toward the right as viewed in the drawing, the deflection of the wheels from the straight track is begun by switch rail 2 before the wheels reach the point of rail 2^a, so that all danger of the wheel flanges encountering the point of rail 2^a is avoided, and the operation of cars or trains over the switch is smoother than when the points of the two rails are directly opposite each other.

The movable rails of this switch are actuated by a switch operating mechanism which, as here shown, is located wholly be-

tween the rails of the switch. Referring now to Figs. 1, 2 and 3, this mechanism comprises a base plate 4 carrying a number of upright studs 14 provided with rollers 5. Between these rollers is a motion plate 3 which is arranged to reciprocate in a direction substantially parallel to the rails of the track. This plate may be reciprocated by any suitable means, this means as here shown 10 being a fluid pressure motor device comprising a cylinder 6 and a piston 7, the piston being operatively connected with the motion plate 3 by means of a jaw 8 on the motion plate and a button 9 on the end of the piston 15 rod.

The motion plate 3 is provided with two cam slots 10 and 10^a spaced longitudinally along the plate as shown in Fig. 1, the middle portion of each slot being disposed at an 20 angle to the direction of movement of the plate, and the end portions of each slot being parallel to this direction of movement. These two cam slots coöperate with two switch rail operating members A and B 25 whereby reciprocation of the motion plate causes the switch rails to be actuated. Each operating member comprises a socket 16 attached to the switch rail as nearly at the rail point as possible, a rod 11 connected at one 30 end with the socket in a manner hereinafter explained, a member 19 connected with the other end of the rod and the structure and function of which will appear hereinafter, and two bars 17 and 18 attached to member 35 19 and arranged to straddle the motion plate 3, as shown most clearly in Fig. 3. Passing through these two bars 17 and 18 is a pin 12 (see Fig. 3) which carries a roller 13, which roller is located in the corresponding cam 40 slot 10 or 10^a and coacts therewith to actuate the operating members A and B.

The two operating members A and B are connected with the two switch rails at substantially the points of these rails, and the 45 two members project inwardly from said rails at substantially right angles thereto, so that these members are staggered to correspond to the staggering of the points of the switch rails. The spacing of the cam slots 50 10 and 10^a along the motion plate 3 corresponds to the staggering of the operating rods 11 and 11^a, so that the two rollers 13 always occupy corresponding positions in the two slots 10 and 10^a.

The operation of the mechanism as thus far described will now be clear. When the motion plate 3 occupies the position, in which it is shown in Fig. 1, the rollers 13 occupy the left-hand ends of the slots 10 and 60 10^a, so that the switch rails are locked in the positions in which they are shown. When the motion plate is shifted to the left, no movement of the switch rails takes place during the first portion of the movement of 65 the plate because the ends of the slots are

parallel to the direction of the plate movement; during the middle portion of the movement of the plate, however, the operating members A and B are shifted transversely with respect to the rails due to the 70 angular disposition of the middle parts of the cam slots, so that the switch rails are then shifted to the positions opposite to those in which they are shown in Fig. 1; during the last portion of the movement of 75 the motion plate, no movement of the switch rails takes place, but these rails then become locked in the positions to which they have been shifted. The reverse operation of the switch rails takes place in a manner which 80 is obvious from the foregoing.

It will now be clear that by virtue of the structure thus far described, each switch rail is moved by a force which is directly and positively applied to the rail at substantially 85 the point of the rail, in spite of the staggered relation of these points. Another valuable feature of the structure is the provision it possesses for minimizing the evil effect of "creeping" switch rails upon the adjustment of the operating mechanism. In the present structure the action of the motion plate is transmitted directly to one end of each operating member and not, as in previous devices employing motion plates, in- 90 directly through the medium of a transverse slide bar in which the pin and roller are mounted. By virtue of this direct method of operation, materially longer operating members may be used than heretofore, and, 95 consequently, a given amount of creeping of the switch rails causes a correspondingly lesser deflection of the operating members from their true paths, these paths being at right angles to the rails. Excessive deflection of these members, of course, foreshortens them in effect, and, hence reduces the pressure with which the switch rail is held closed. The greater the length of the operating members, therefore, the more constant 100 may the switch rail pressure be maintained.

Fitting over the upper ends of the studs 14 is a cover plate 15, which plate is shown in Figs. 2 and 3 but is removed in Fig. 1 to more clearly show the parts of the apparatus 115 under the cover. The studs are reduced at their upper ends to form shoulders 14^a on which this cover rests, and the reduced portions of the studs are threaded to receive nuts 14^b which hold the cover in place. This 120 cover serves to hold the motion plate 3 and the bars 17 and 18 in their proper horizontal planes, and together with the bottom plate it serves to hold the operating members A and B in their proper paths of movement. These functions are accomplished by virtue 125 of the following structure. As shown in Figs. 2 and 3, the base plate is provided with two transverse channels 4^a, 4^b located directly in the path of movement of the bars 13

17 and 18, and the cover plate is provided with two similar transverse channels 15^a, 15^a directly above the channels in the base plate. Each pin 12 carries two additional rollers 5 20 and 21, located respectively above the bar 17 and below the bar 18, which rollers are located in the channels 15^a and 4^a respectively. The diameter of these rollers is only slightly less than the width of the channels, so that 10 free longitudinal movement of the operating members A and B is permitted, while movement of the motion plate ends of these members in the direction of movement of the motion plate 3 is prevented. Obviously, upward movement of the motion plate and operating members is prevented by the engagement of the upper surfaces of rollers 20 with the seats of the channels 15^a, 15^a.

Inasmuch as the locking of the switch is 20 accomplished by the operating members A and B, it is desirable to provide means for avoiding failure of the locking function in the event of breakage of the pin 12 or roller 13 of either of these members. For this reason, we preferably provide two steel blocks 22, 22 (Figs. 1 and 3), which are attached to the motion plate 3 by rivets 23, which blocks are so located on the motion plate that when either switch rail is against its adjacent stock rail, the inner end of the corresponding operating member A or B abuts against one of these blocks. In Fig. 3 the end of bar 18 of member A is shown abutting against one of the blocks 22. In other words, these two blocks are located adjacent the left-hand end of cam slot 10 and the right-hand end of cam slot 10^a as viewed in Fig. 1. The locking of the switch is accomplished, then, by these blocks as well as by 40 the coaction of the cam slots and rollers 13, and will be accomplished by the blocks alone in the event of shearing of pin 12.

It will be clear that if the switch rails are 45 reversed by the trailing of a car or train through the switch, serious damage will be done to some part of the operating apparatus unless means are provided to avoid such damage, or if the switch fails to open the car or train will mount the switch rails and be derailed. For these reasons we preferably provide each operating member A and B with the member 19 (see Fig. 1) which constitutes a "weak link" in the member. Each member 19 is in the form of a stirrup, 50 the arms of which are attached to the bars 17 and 18, and the cross piece of which is attached to the rod 11. In the event that a train trails through the switch when the latter is set for the other route, the cross pieces 55 of these members will collapse and so allow the switch to open but prevent serious damage to the operating apparatus. The members 19 can then be easily replaced, whereupon the switch will again be ready for 60 service. This provision also renders more

certain the switch rails, after being trailed through by a train, being left in their open positions and hence more certain the intended function of a circuit controller actuated by the rails to open signal circuits in 70 event of this occurrence.

Referring to Fig. 1, the rods 11 of the operating members A and B are not rigidly attached to the sockets 16. On the contrary, each socket is provided with a recess 16^a in 75 which a head 11^a on the rod is free to move. Each switch rail is positively moved toward and held against its adjacent stock rail by the engagement of the corresponding head 11^a with the bottom of the socket 16^a, but 80 each switch rail is drawn away from its adjacent stock rail by the other switch rail through the medium of the tie members 24, 24^a, etc. connecting these rails together. As will be observed from the gap between the 85 head of rod 11 and the base of socket 16 at rail 2^a, the throw of the switch rails is less than the stroke of the operating members A and B. The switch operating members are made adjustable for length. It follows, 90 then, that a greater stroke may be given to the operating members than is necessary for a newly fitted switch, in order to meet the increasing throw made necessary by wear during the life of the switch. Another feature 95 of this construction is that it permits of varying the throw of the switch rails without necessitating the substitution of a new motion plate 3. That is, the switch rail throw may be varied by merely varying the 100 lengths of the members 24, 24^a, etc.

In Fig. 1 we have shown a circuit controller C, which controller is illustrated in detail in Figs. 4, 5, 6 and 7. This circuit controller is mounted on a plate 25 (see Figs. 105 2, 6 and 7) which is attached to the under side of base plate 4 by bolts 25^a. The controller comprises a box 26 attached to an overhanging part of the plate 25, which box is closed by a hinged cover 27 (omitted from 110 some of the views). The box contains a drum 28 of insulating material journaled to oscillate in bearings 28^a mounted in the walls of the box, and on the drum are two pairs of contact members 29, 29^a and 30, 30^a. Co- 115 operating with these contact members are a plurality of contact fingers designated 31, 31^a, 32, 32^a, 32^b, 32^c, 33 and 33^a, which fingers are mounted in a way which will be explained hereinafter.

The drum 28 is operatively connected with the motion plate 3, to be rocked thereby, in the following manner. The under surface of the motion plate 3 is provided with a cam groove 34 shaped as shown in Fig. 1, 125 the middle portion of this groove being parallel to the direction of movement of the plate and the ends being at angles to this direction as shown. Co-acting with this cam slot is a follower 35 (Figs. 2 and 6) in the 130

form of a roller which is mounted on a stud 36. This stud is carried in one end of an arm 37 the other end of which is attached to a journal pin 38 pivotally mounted on the base 5 plate 4 (Figs. 1 and 2). It will be seen, therefore, that reciprocation of the motion plate 3 will cause oscillation of the stud 36 around the stud 38 as a center. This movement of stud 36 causes reciprocation of a bar 39 (Figs. 10 1, 2 and 6) which is pivotally connected with the stud 36 and which slides in a groove 40 in the plate 25, this groove being wide enough, as shown in Fig. 2, to permit of the slight lateral motion of the bar due to the 15 fact that the movement of stud 36 is in an arc of a circle. The end of the bar 39 opposite to the stud 36 is provided with teeth to form a rack 39^a which meshes with a segmental gear 41 attached to the contact drum 20 28, so that reciprocation of the bar causes oscillation of the drum about its journals.

The parts of the drum operating apparatus are so proportioned that contact members 29, 29^a, or contact members 30, 30^a, are 25 contiguous to the free ends of contact fingers 31 to 33, according as the motion plate is in one extreme position or the other, that is, according as the switch is locked in one extreme position or the other. In Fig. 4 30 the drum is shown in an intermediate position wherein none of the contact members are contiguous to the contact fingers, in order to illustrate all of the contact members in this view.

35 The four middle contact fingers 32, 32^a, 32^b and 32^c are constantly in the path of the drum-carried contact members, these fingers (see Figs. 6 and 4) being attached to a block 42 of insulating material which is rigidly attached to a frame 43, which frame in turn is fixed to the bottom of the controller box 26.

The outer pair of contacts 31, 31^a is, however, so mounted that these contacts may be 45 raised out of the path of their co-operating drum-carried contact members, and the other outer pair of fingers 33, 33^a are mounted in a similar manner. The fingers 31, 31^a (see Fig. 7) are mounted on a block 50 44 of insulating material which is attached to a frame 45 mounted to swing about a rod 46 carried in the controller box. This frame is biased by a spring 49 to such position that the fingers are in the path of the drum carried contact members, but may be raised out of such position against the action of the spring by a tappet 47 which is controlled as hereinafter explained. Fingers 33 and 33^a are carried by a block 44^a (Fig. 4) which is 55 60 pivotally mounted and controlled in the same manner as block 44.

The tappet 47 for fingers 31, 31^a and the corresponding tappet (not shown) for the other movable fingers, are controlled by the 65 two movable switch rails 2 and 2^a respec-

tively, this control being through the medium of two slide bars 48 and 50 (Figs. 1, 2, 5 and 7). Bar 48 is connected directly with switch rail 2 by a rod 51, while bar 50 is connected with a rod 52 which turns back 70 on itself and is attached to rail 2^a. The two bars 48 and 50 reciprocate in slots 53 and 54 respectively in the plate 25, and pass directly under the two tappets 47. These two bars are provided with V-shaped transverse 75 grooves 48^a and 50^a respectively (Fig. 7) which coact with the V-shaped ends of the corresponding tappets 47. When a tappet 47 is in the groove of its corresponding bar, the contact fingers controlled by such 80 tappet are in the path of the drum-carried contact members, but when the bar is moved so that its groove does not register with the tappet, the tappet raises its fingers out of the path of the contact members. The rods 51 85 and 52 which connect the bars 48 and 50 with the switch rails are adjustable for length, so that the proper relation may be secured and maintained between the switch rails and the contact fingers. 90

The slide bars 48 and 50, and the grooves 48^a and 50^a in these bars, are so arranged that the groove in bar 48 registers with the corresponding tappet 47 only when switch rail 2 is tight against its stock rail 1. If the motion plate 3 is then in the position for locking this rail in such position, contact members 29 and 29^a are contiguous to fingers 31 and 31^a, so that the contact between these members and fingers is closed. Similarly, the groove 50^a in bar 50 registers with the tappet for fingers 33 and 33^a only when switch rail 2^a is tight against stock rail 1^a, whereby if the motion plate 3 is then in corresponding locking position these fingers engage with contact members 30 and 30^a. In other words, when the motion plate and switch coincide in position, one pair of contact fingers 31 or 33 engages the corresponding pair of contact members 29 or 30, and the other pair of fingers is raised out of the path of its corresponding contact members. 105

Then if the switch rails should be moved while the motion plate remains stationary, the fingers which engaged their contact members would be raised away from such members; and if the motion plate should be moved while the switch rails remain stationary, the drum 28 would move the contact members away from the fingers which are 110 down. Engagement of a pair of contact fingers with a pair of contact members, then, requires coincidence of motion plate and switch rails in locked position, and one pair of contacts or the other is closed depending 115 on whether the switch is in one extreme position or the other.

The operation of the circuit controller C by the switch and switch operating mechanism is as follows: When the motion plate 13

and the switch rails are in the positions shown in Fig. 1, the drum 28 occupies the position in which it is shown in Figs. 6 and 7, and contact fingers 31 and 31^a are down so that these fingers are in engagement with drum-carried contact members 29 and 29^a. Assume now that the motion plate 3 is shifted to the left, as viewed in Fig. 1 to reverse the position of the switch. During the first part of this movement, no motion of the switch rails takes place, because of the parallel end portions of the cam slots 10 and 10^a, but during this first portion of the movement of the motion plate (while the switch is being unlocked) the circuit controller drum 28 is shifted to its middle position wherein none of the contact members carried thereby are contiguous to the contact fingers. This movement of the drum is, of course, due to the inclined end portion of cam groove 34, which operates the slide bar 39 (Fig. 6). All contacts in the circuit controller are now open and will remain open as long as the roller 35 occupies the straight middle portion of the cam slot 34. The switch rails are then shifted by the further movement of the motion plate 3, and when this shifting is completed, that is, after the end portions of the cam slots have reached the rollers 13, the circuit controller drum 28 is shifted through the remainder of its stroke (while the switch is being locked), so that contact members 30 and 30^a are contiguous to contact fingers 33 and 33^a. If the switch rails have completed their movement in response to the movement of the motion plate, contact fingers 33 and 33^a will be released by the registry of slot 50^a in slide bar 50 with the tappet 47 which controls these fingers, so that these fingers will then fall into engagement with their contact members 30 and 30^a. The first part of the movement of the switch rails, of course, raised contact fingers 31 and 31^a out of the path of contact members 29 and 29^a, but this is immaterial so long as the mechanism operates in the manner intended, because these contact members were shifted out of engagement with their contact fingers before the movement of the switch rails began (during the unlocking of the switch).

Referring now to Fig. 8, we have here shown one arrangement of circuits which may be used in conjunction with the circuit controller C shown in the preceding views. K^N and K^R represent the usual indication magnets included in an interlocking machine, which magnets govern the movements of the lever, which in turn governs the switch operating mechanism. S^N and S^R are two signals governing traffic through the switch.

Indication magnet K^N is controlled by a circuit from battery B through contact finger 32, contact member 29^a, finger 31^a, mag-

net K^N, to common wire O. This circuit is closed when the drum 28 is in the position shown in the drawing, provided that finger 31^a is in engagement with member 29^a; that is, provided that the switch rails are in the extreme position corresponding to the position of the motion plate 3. The circuit for the signal S^N is from battery B through contact fingers 32^a, contact member 29, finger 31, operating mechanism of signal S^N to common wire O.

When the motion plate and the switch are reversed in position, contact members 30 and 30^a will engage with fingers 32^b, 32^c, 33^a and 33, so that indication magnet K^R will become energized and the circuit for the signal S^R will be closed at the circuit controller C. A train trailing through either rail will thus interrupt the contacts included in the control of that signal which pertains to that rail, and largely by reason of the collapse of the yielding member 19 of the switch operating member already referred to.

It is understood, of course, that the circuits for the indication magnets and for the signals will usually be governed by apparatus other than that shown in Fig. 8, but inasmuch as such other apparatus forms no part of our present invention it is eliminated from this view in order to simplify the drawing.

Although we have herein shown and described only one form of switch operating apparatus embodying our invention, it is understood that various changes and modifications may be made therein within the scope of the appended claims without departing from the spirit and scope of our invention.

Having thus described our invention, what we claim is:

1. In combination, a railway switch having switch rails the points of which are staggered longitudinally with relation to the track; and a switch operating mechanism comprising a motion plate movable in a direction substantially parallel to the track and having two longitudinally spaced cam slots, and two operating members one for each switch rail and co-operating with said two cam slots respectively.

2. In combination, a railway switch having switch rails the points of which are staggered longitudinally with relation to the track; and a switch operating mechanism comprising two members connected with said switch rails respectively adjacent the points thereof and disposed substantially at right angles to the rails, a motion plate movable longitudinally with respect to said rails and having two longitudinally disposed cam slots co-operating with said two members respectively, and means for reciprocating said motion plate.

3. In combination, a railway switch comprising movable switch rails rigidly connected by tying members for simultaneous movement; and means for moving said switch rails in reverse directions comprising two operating members one for each switch rail for moving the switch rail toward the corresponding stock rail but not for movement of the switch rail in the other direction.
4. In combination, a railway switch comprising movable switch rails rigidly connected by tying members for simultaneous movement; and an operating mechanism comprising operating members one for each switch rail, a socket attached to each switch rail and having a recess opening toward the middle of the track, and a head on each operating member coöperating with the bottom of said socket recess to positively drive

the switch rail toward and hold it against the adjacent stock rail.

5. Railway switch operating apparatus comprising a rod connected with a rail of the switch, a rod connected with the switch operating mechanism, and a stirrup-shaped weak member the arms of which are connected with one of said rods and the cross-piece of which is attached to the other rod.

In testimony whereof we affix our signatures, each in the presence of two witnesses.
